MACHINE FOR PRODUCING TOBACCO
PORTIONS OF UNIFORM SIZEKarl Erik Granstedt, Stockholm, Sweden, assignor
to Aktiebolaget Formator, Stockholm, Sweden,
a joint-stock company of Sweden

Application June 14, 1933, Serial No. 675,829

11 Claims. (Cl. 131—39)

The present invention relates to machines for producing tobacco portions of uniform size and more particularly to those of a known kind in which a tobacco mass is compressed in an open ended casing onto a bed whereupon the projecting tobacco portion is severed from the remaining tobacco mass close by the casing.

Machines of this kind as hitherto known act satisfactorily when the tobacco mass treated is of uniform nature and quality. It may, however, occur that the tobacco mass treated is more or less moist or subjected to frequent variations in structure. If the tobacco portions are intended for the manufacture of cigars it may also occur that binders or wrappers of different sizes are used. In all cases now mentioned a material is obtained which does not render a finished product of uniform size, though the size of said material is uniform.

According to my present invention a machine mainly of the construction described above is provided with a device admitting a rapid and easy adjustment of the position that the casing occupies when the cutting operation is effected for the purpose of encountering periodical changes of the quality of the tobacco mass etc. as above mentioned, even though such changes may appear in the course of operating the machine.

A main object of my invention is to provide a machine of said type with means operable at the outside of the machine for adjusting the cutting position of the casing.

A further object of my invention is to provide the mechanism for reciprocating the casing with means operable at the outside of the machine for adjusting the cutting position of the casing.

With these and other objects not specifically mentioned in view, my invention consists in certain constructions, combinations and parts which will be hereinafter fully described and then specifically set forth in the claims hereunto appended.

In the accompanying drawings, which form part of this specification, and in which like characters of reference indicate the same or like parts, Fig. 1 is a side elevational view of a machine constructed in accordance with the invention; Fig. 2 is a front elevational view of part of the machine; Fig. 3 is a sectional view on line III—III of Fig. 2; Fig. 4 is a front view on larger scale of part of the machine; Fig. 5 is a vertical section on line V—V of Fig. 2; Fig. 6 illustrates the lower part of Fig. 5 in a different operating posi-

tion; and Fig. 7 is an elevational view of a modified part of the machine.

Referring to the drawings, a casing 1 having openings at the top and the bottom is provided with an opening in its rear wall, said opening communicating with a funnel 2. Inserted through the top opening of the casing is a piston 3 fitting the interior of the casing. Projecting from the sides of the casing are pins 4, and to each of them a double-armed lever 5, 6 is pivoted. The arms 6 have toothed segments or curved racks 7 at their upper free ends, and said curved racks engage similar racks 8 on arms 9, keyed to a horizontal shaft 10 rotatable in bearings 11 on a slide 12. Rigidly connected to one end of the shaft 10 is one end of an arm 40, the other end of which is pivotally connected to a rod 41 reciprocated by any suitable mechanism in such manner that double-armed lever 5, 6 obtains swinging movements. Secured to the lower end of the arms 5 is a cutter 13. The lateral walls 14 of the casing are provided with lugs 15, by which the casing is secured to the slide 12, the latter running on vertical guide bars 16, which are connected with each other at the top by means of a cross bar 17 carrying the piston 3, and which are in turn slidable in vertical guides 18 in a table 19.

Reciprocating movements are imparted to the slide 12 by means of rods 20, the top end of which is keyed by means of a pin 21 to a socket 22, the top of which has small radial grooves 23. The socket 22 is provided with a laterally projecting handle 33. Another socket 24 is slidably mounted on a connecting member 25 and each of said members is connected to the slide 12 by means of a screw 26. A pin 27 in the socket 24 projects into a vertical groove 28 in the member 25 and prevents rotary movement of the socket 24 relative to the member 25. A coiled compression spring 29 engages the bottom of the member 25 and a bottom plate 30 of the socket 24, said plate having ridges corresponding to the grooves 23 of the socket 22. The connecting member 25 is internally threaded and the corresponding threaded top end 31 of the rods is screwed thereto. The other end of the rods is screwed to a link 32 pivoted to one arm 33 of a bell crank lever on a shaft 34. The threads of the lower end of the rod have a direction opposite to that of the threads of the upper end of the rod. The other arm 35 of the lever is provided with a roller 36. A coiled tension spring 37 forces the roller 36 against the periphery of a cam disc 38 keyed

to a continuously rotating drive shaft 39, connected to any known driving device.

In operating the machine shown in the drawings tobacco mass is fed into the funnel 2, when 5 the piston 3 occupies its uppermost position as shown in Fig. 5. Thereupon the casing with the knife 13 is moved into a position at a certain distance from the upper surface of the table 19, whereupon tobacco mass is fed onto the table by 10 the piston whereupon the knife 13 is swung inwards, thus severing the projecting part of the tobacco mass. Movement is imparted to the casing by means of the rods 20, which are actuated by the bell crank lever 33, 35 and the cam disc 15 38. The roller 36 rides on the concentric part of the periphery of the cam disc for about half a revolution and thereby the casing 1 occupies its uppermost position. If the quality of the tobacco or the size of the wrapper varies during 20 the course of operation and thereby adjustment is required the handle 33 with the rod 20 is turned into a desired position whereby the rod is shortened or lengthened so that the lowermost position of casing 1 may be adjusted particularly 25 easily. The position of the socket 22 relative to the socket 24 may be determined by the ridges of the latter when they engage the grooves 23. The socket 22 or the socket 24 may be graduated. By the adjusting device now disclosed the device 30 is operated very easily as the handle 33 may be turned into a desired position during the period when the roller 36 rides on the concentric part of the cam disc 38, that is when the casing occupies its uppermost position. If desired the same 35 direction but a different pitch may be given to the threads of the rod 20 as shown in Fig. 7. Thereby an extremely exact adjustment is obtained by turning the rods.

What I claim as new and desire to secure by 40 Letters Patent in the United States of America is:

1. In a machine for producing tobacco portions of uniform size, a bed, an open ended casing, a piston for compressing tobacco mass in the casing onto the bed, a cutter for severing the projecting portion of the tobacco mass close by the casing, means for moving the casing to a cutting position within a predetermined distance of the bed, and means operable at the side of the casing for adjusting said casing relative to said bed.

2. In a machine for producing tobacco portions of uniform size, a bed, an open ended casing, a piston for compressing tobacco mass in the casing onto the bed, a cutter for severing the projecting portion of the tobacco mass close by the casing, means for moving the casing to a cutting position within a predetermined distance of the bed, and manually operable means at the side of the casing for adjusting said casing relative to said bed.

3. In a machine for producing tobacco portions of uniform size, a bed, an open ended casing, a piston for compressing tobacco mass in the casing onto the bed, a cutter for severing the projecting portion of the tobacco mass close by the casing, means for moving the casing to a cutting position within a predetermined distance of the bed, and manually operable yielding means at the side of the casing for adjusting said casing relative to said bed.

4. In a machine for producing tobacco portions of uniform size, a bed, an open ended casing, a piston for compressing tobacco mass in the casing onto the bed, a cutter for severing the projecting portion of the tobacco mass close by the casing,

means for moving the casing to a cutting position within a predetermined distance of the bed, and means operable at the side of the casing for adjusting said casing into several distinct positions relative to said bed.

5. In a machine for producing tobacco portions of uniform size, a table, a vertically movable casing above the table, a piston for compressing tobacco mass in the casing onto the table, a cutter for severing the projecting portion of the tobacco mass close by the casing, means for moving the casing vertically to a cutting position relative to the table, and means operable at the side of the casing for adjusting said casing into a vertical position relative to said table.

6. In a machine for producing tobacco portions of uniform size, a bed, an open ended casing, a piston for compressing tobacco mass in the casing onto the bed, a cutter for severing the projecting portion of the tobacco mass close by the casing, a mechanism for moving the casing to a cutting position within a predetermined distance of the bed, said mechanism having means at the side of the casing for adjusting said casing relative to said bed.

7. In a machine for producing tobacco portions of uniform size, a bed, an open ended casing, a piston for compressing tobacco mass in the casing onto the bed, a cutter for severing the projecting portion of the tobacco mass close by the casing, driving means for moving the casing to a cutting position within a predetermined distance of the bed, and rods connecting said driving means with the casing and having means operable at the side of the casing for adjusting said casing relative to said bed.

8. In a machine for producing tobacco portions of uniform size, a bed, an open ended casing, a piston for compressing tobacco mass in the casing onto the bed, a cutter for severing the projecting portion of the tobacco mass close by the casing, driving means for moving the casing to a cutting position within a predetermined distance of the bed, rods having ends connected to the casing and other ends connected to said driving means, and means operable at the side of the casing for adjusting the connection of the rod with the casing.

9. In a machine for producing tobacco portions of uniform size, a bed, an open ended casing, a piston for compressing tobacco mass in the casing onto the bed, a cutter for severing the projecting portion of the tobacco mass close by the casing, driving means for moving the casing to a cutting position within a predetermined distance of the bed, rods having ends connected to the casing and other ends connected to said driving means, and means operable at the side of the casing for adjusting the connection of the rod to said driving means.

10. In a machine for producing tobacco portions of uniform size, a bed, an open ended casing, a piston for compressing tobacco mass in the casing onto the bed, a cutter for severing the projecting portion of the tobacco mass close by the casing, driving means for moving the casing to a cutting position within a predetermined distance of the bed, rods having threaded ends one end of each rod being connected to the casing and the other end of each rod being connected to said driving means and the threads of one end having a pitch different from that of the other end of each rod, and adjusting means operable at the side of the casing for turning said rods.

11. In a machine for producing tobacco por-
